UNITED STATES PATENT OFFICE

ARTHUR M. SCHUSTER, OF MIDWEST, WYOMING

CLEANER FOR SUCKER RODS AND THE LIKE

Application filed January 18, 1929. Serial No. 333,434.

In withdrawing sucker rods from oil wells, many of which are 2000 or 4000 feet or more in depth, the accumulation of wax and heavy oil on the sucker rod becomes a matter of serious consideration. Everything around the top of the oil well becomes covered with this oil and wax, which of itself is very objectionable. Moreover, this heavy wax and oil if not removed accumulates quantities of sand while out of the well which is returned to the well, and this sand settles to the bottom of the well where it causes trouble in the pump. Various schemes for taking care of this very objectionable material have been suggested, but heretofore none of them has been commercially feasible. This invention, therefore, precludes the necessity for pulling the rods except at longer intervals.

An object of this invention is to provide a means for removing the oil and wax from the sucker rod as it is pulled from the oil well.

This and other objects, as will hereinafter appear, are accomplished by this invention, which is fully described in the following specification shown in the accompanying drawings in which—

Figure 1 is a side elevation of the device applied to the tubing of an oil well;

Fig. 2 is a longitudinal vertical section on the line 2 of Fig. 3;

Fig. 3 is a horizontal section on the line 3 of Fig. 2 showing that portion of the apparatus below this line in plan;

Fig. 4 is a section on the line 3 of Fig. 2 but lies in the opposite direction;

Fig. 5 is a partial enlarged view of the upper portion of the device shown in Fig. 2 showing a rod coupling passing through the upper rubber scraper;

Fig. 6 is a partial enlarged view of one of the cleaner elements showing a coupling passing therethrough;

Fig. 7 is a section through a modified form top rubber scraper; and

Fig. 8 is a broken side elevation of a sucker rod showing the couplings and wooden rod protectors.

The embodiment illustrated comprises a hollow frame 10 adapted to be secured to the

tubing A of the oil well as by means of complementary threaded portions on these tube members, as shown. The sucker rod B extends through the hollow frame 10 and down through the tubing A to the oil pump.

The frame 10 is preferably made of malleable iron, as it must necessarily be quite strong as will hereinafter appear. While ribs are omitted for the sake of clearness, it will be understood that this frame will be suitably ribbed to give it the necessary strength and rigidity without at the same time adding too greatly to its weigh.

The frame 10 is provided with a series of openings as 11 which are preferably uniformly spaced about the axis of the cleaner and of the pump rod B, as will be seen by reference to Fig. 3. Into each of the openings 11 is inserted a holder 12 which passes therethrough, as is shown in Fig. 2, the holder being secured in place by means of cap screws 13.

A plunger 14 is slidably mounted within the holder 12 and is normally forced inwardly by means of a spring 15, a set collar 16 secured upon the reduced extension of the plunger serving to limit its inward travel.

The plunger 14 carries at its inner end a scraper element 17 which as shown in Figs. 3 and 6 is substantially C-shaped so as to normally surround the pump rod B. This scraper element is preferably made up of cotton webbing and vulcanized rubber, such as is to be found in rubber belting and the like. The purpose of this is to provide a certain amount of strength and rigidity to the element 17 so as to cause it to act as a scraper upon the sucker rod B, at the same time being sufficiently yielding to permit the passage therethrough of rod couplings, wooden rod protectors, and the like.

The rod comes in lengths which are connected by means of couplings C which are screwed therein. To add further to the difficulties of cleaning a pump rod of this kind, the rod may be provided at intervals with wooden rod protectors D which are secured on the rod by means of metal rings E which are driven down over the tapered ends of the wooden rod protectors D. The purpose of

these protectors is to prevent the rod from rubbing against the tubing A while pumping oil or while the rod is being withdrawn from the tubing or inserted therein. Any device, therefore, which is used for cleaning the sucker rod must be able to pass both the couplings C and the even larger wooden rod protectors D.

The cleaner of the present invention does 10 this by making the scraper member 17 C-shaped so that when it engages the rod B as is shown in Fig. 3, it almost completely surrounds it. At the same time this member is sufficiently yielding to enable it to open in 15 order to pass either the coupling C or the wooden protectors D. All of these members are substantially cylindrical in form so that in passing through the member 17 it closely surrounds them at all times, thereby very 20 effectually scraping the oil and wax therefrom.

It will be observed that the scraping elements are preferably three in number and disposed about the axis of the rod B so as 25 to exert pressure thereon at different points as the rod is passing through the cleaning device.

The frame or casing 10 is preferably 30 closed at the top by means of a cap 18 which fits thereover, and is secured thereto as by means of screws 19. An elastic closure member 20, such as rubber, is centrally perforated and secured within a central opening in the cap 18 as by means of a plate 21 35 which is secured on the cap by means of screws 22. As the rod B passes upwardly through the rubber closure member 20, most of the wax and oil is loosened and removed by the scraper members 17, substantially all 40 of the balance being removed by the closure member 20.

As the wax is removed from the sucker rod B by the scraper members 17, it passes 45 out through suitable openings 10^a, 10^b, 10^c, and the like in the frame of casing 10. These openings are made as large as possible to allow the easy egress of the accumulated oil and wax which has been scraped off the rod. In order to prevent weakening 50 of the frame 10 due to these large openings, suitable ribs (not shown) may be employed for additional strength and rigidity.

As the rod passes upwardly through this body of wax, much of which has been removed from the rod, it has a tendency, particularly due to the enlargement C and D, to pick up some of this wax and carry it out through the top of the scraper. This, however, is prevented by the top closure including the rubber scraper member 20. For this purpose the rubber member 20, as well as the rubber of the scraper member 17, is preferably treated to render it impervious to the action of the oil.

65 It will be observed that the annular plate

21 is flat on top and thus serves as a convenient ledge on which to rest the tools which serve to hold the sucker rod while the sucker rod section which has just emerged from the holder is being unscrewed from the coupling. 70 For this purpose the frame 10 must be made strong enough to support the weight of the entire sucker rod and tools, which sometimes amounts to several tons.

In Fig. 7 is shown a modified form of top 75 rubber scraper member 23 which, if desired, can be used in place of the member 20 shown in Fig. 5.

By the time the sucker rod has passed the three scraper members 17 and the top member 20, substantially all the wax and oils have been removed from the rod so that the sucker rod can now be withdrawn from the well without the operator becoming covered with oil as heretofore. Actual tests in the 85 oil fields have shown this to be a fact. The wax thus recovered is also quite valuable.

While I have shown and described but a single embodiment of my invention, it is to be understood that it is capable of many modifications. Changes, therefore, in the construction and arrangement may be made which do not depart from the spirit and scope of the invention as disclosed in the appended claims. 95

I claim:

1. In a sucker rod cleaner, the combination of a hollow frame, and a plurality of vertically spaced yieldable scraper elements slidably mounted in said frame and projecting 100 inwardly thereinto at different angles about the axis of the rod, said frame having a horizontal ledge about the top adapted to support a rod-holding tool.

2. In a sucker rod cleaner, the combination of a hollow frame, and a plurality of vertically spaced yieldable scraper elements slidably mounted in said frame and projecting inwardly thereinto at different angles about the axis of the rod, said elements having 110 C-shaped openings in the end adapted to closely make contact with the sucker rod and to yield to permit enlargements thereon to pass through the scraper element.

3. In a sucker rod cleaner, the combination of a hollow frame, and a plurality of vertically spaced yieldable scraper elements, yieldably mounted in said frame and projecting inwardly thereinto at different angles about the axis of the rod, said elements having 115 C-shaped openings in the end adapted to closely make contact with the sucker rod and to yield to permit enlargements thereon to pass through the scraper element.

4. In a sucker rod cleaner, the combination of a hollow frame adapted to have a sucker rod pass therethrough, a plurality of holes in the side of said frame spaced about the axis of said rod, a holder secured in each of said holes, and a flexible scraping element 120

130

slidably and yieldably mounted in each of said holders, said elements being yieldable to permit enlarged elements on the sucker rod to pass therethrough.

5 5. In a sucker rod cleaner, the combination of a hollow frame adapted to have a sucker rod pass therethrough, a plurality of holes in the side of said frame spaced about the axis of said rod, a holder secured in each of 10 said holes, a flexible scraping element slidably mounted in each of said holders, and a spring urging each of said scraper elements towards said scraper rod, said elements being yieldable to permit enlarged elements 15 on the sucker rod to pass therethrough.

6. In apparatus of the class described, a sucker rod cleaning member comprising a thick block of rubber-like material having a hole adapted to closely surround a sucker 20 rod and a slot from said hole to one side of the block, and means for holding said block.

In testimony whereof, I have hereunto set my hand this 5th day of January, 1929.

ARTHUR M. SCHUSTER.
